DESIGN FOR A FLUORESCENT LAMP FIXTURE

Charles F. MacCarthy, Salem, Mass., assignor to
Hygrade Sylvania Corporation, Salem, Mass., a
corporation of Massachusetts

Application May 28, 1940, Serial No. 92,650

Term of patent 7 years

To all whom it may concern:

Be it known that I, Charles F. MacCarthy, citizen of the United States, residing at Salem, in the county of Essex and State of Massachusetts, have invented a new, original, and ornamental Design for a Fluorescent Lamp Fixture, of which the following is a specification, reference being had to the accompanying drawing, forming part thereof.

Figure 1 is a bottom perspective view of a flu-

orescent lamp fixture according to my new design.

Figure 2 is a top plan view of the same fixture.

Figure 3 is a fragmental cross sectional view of the fixture, taken on the line 3—3 in Fig. 2.

I claim:

The ornamental design for a fluorescent lamp fixture, as shown and described.

CHARLES F. MACCARTHY.
